UNITED STATES PATENT OFFICE

ALBERT CARL MOWITZ, OF PHILADELPHIA, PENNSYLVANIA, ASSIGNOR TO RADIO CABINET MANUFACTURING CORPORATION, A CORPORATION OF ILLINOIS

DESIGN FOR A RADIOCABINET

Application filed February 11, 1929. Serial No. 30,011. Term of patent 3½ years.

To all whom it may concern:

Be it known that I, ALBERT CARL MOWITZ, a citizen of the United States, residing at Philadelphia, in the county of Philadelphia and State of Pennsylvania, have invented a new, original, and ornamental Design for Radiocabinets, of which the following is a specification, reference being had to the accompanying drawing, forming part thereof.

Figure 1 is a perspective view of the radio

cabinet showing my new design with the doors closed.

Figure 2 is a similar perspective view showing the doors opened.

I claim:

The ornamental design for a radiocabinet as shown.

In testimony whereof I affix my signature at Philadelphia, Pa., Feb. 5th, 1929.

ALBERT CARL MOWITZ.
